UNITED STATES PATENT OFFICE.

STANLEY W. YARDER, OF TOLEDO, OHIO.

DESIGN FOR A TOOL BOX.

Application filed May 23, 1921. Serial No. 471,990. Term of patent 7 years.

To all whom it may concern:

Be it known that I, STANLEY W. YARDER, a citizen of the United States, residing at Toledo, in the county of Lucas and State of Ohio, have invented a new, original, and ornamental Design for a Tool Box, of which the following is a specification, reference being had to the accompanying drawing, forming part thereof.

The figure is a perspective view illustrating a tool box, showing my new design.

I claim:

The ornamental design for a tool box, as shown.

STANLEY W. YARDER.

Witnesses:

LEONARD F. ZYTKUS,
JOS. MALIKOWSKI.
